METHOD OF PHOTOGRAPHY OF A RACE

Lester E. Bernd, Wellesley Hills, Mass., assignor
to The Delaware Steeplechase and Race Asso-
ciation, Wilmington, Del., a corporation of
Delaware

Application January 8, 1952, Serial No. 265,489

2 Claims. (Cl. 88—16)

1

This invention relates to a method of recording on motion picture film a racing event, such as a horse race, particularly those portions thereof including the backstretch, and the homestretch straightaway to the finish line, and possibly all other portions of the track. More specifically, the invention relates to a method wherein synchronously run cameras obtain a side and front view of the race from the quarter pole to the finish line, and also on the straightaway on the backstretch, and possibly on other portions of the track, provision being made for simultaneously and synchronously projecting the photographs so synchronously taken, side by side upon a movie screen. In this way, a complete analysis of the race upon permanent film is easily recorded for full inspection by the judges only a few minutes after a race has been run.

It has been the practice in the past to employ the use of patrol judges interspersed at given intervals around the track, each of which, with the use of binoculars and mainly by personal observation, obtains a relatively close view of the race at that portion of track nearest them. Often these patrol judges are located at definite spaced points, such as at each one-eighth of a mile. The purpose of such officials is to take notice of any rule infraction, violation, or improper handling committed by jockeys or contestants which may be cause for disqualification of the respective horse, or other official ruling. These patrol judges, as is well known, report such violation to those in charge of the race who determine the penalties to be rendered. It is obvious that by the use of patrol judges to personally observe a portion of the race whether it be on the straightaways or around the curved portions of the track, reliance is placed mainly upon the personal observation of these individuals and, therefore, subject to errors due purely to the human element.

It is apparent also that, for an explicit and exact determination of any rule infraction or foul, a view of the race must be simultaneously had from both a frontal and side position, since in certain instances, a foul observed from the side may not be visible from the front and vice versa—a foul visible from the front may not be seen from a side position.

Although the use of photographs in recording race results, and in determining the winner of a race by photo finish, when the question is close, has long been known; and while film patrol cameras on towers for a running motion picture of the race have also been known at quite a few tracks, heretofore there has been no method devised by which synchronized photographs taken from front and side, at positions giving the optimum view, are so coordinated as to permit recording on a strip of film which enables explicit and exact definition, and which enables precise

2

detection of any improper behavior of the contestants. It is, therefore, a primary object of my invention to provide a method which enables simultaneous photographing on motion picture film of the front and side view of a race throughout the homestretch straightaway and past the finish line, and on other portions of the track, in such manner that practically eliminates the human element, applying to observation of rule infractions, violations, or contestant performance. A proper and accurate determination of any decision as to these matters involving the participants can, therefore, be made by the stewards with the use of my invention which I call the "Two-Way Project."

It is an additional object of this invention to provide a method whereby a single cameraman is in complete control of two cameras located at respective side and frontal positions in order that each of such cameras is accurately started and stopped with the other with split-second timing, thereby insuring at any given moment a true side and front picture of the race.

An additional object of the invention is to provide a method whereby errors in the reporting of rule infractions by patrol judges or other individuals are eliminated, reliance being placed upon the efficiency of mechanical observation of the race in addition to or in lieu of personal observation by any number of such individuals as patrol judges, inspectors, stewards, or other race officials.

In addition, a further objective of this invention is to provide a method whereby motion pictures taken from the front and side in the manner stated are synchronously projected side by side upon a common screen whereby at any given instance the race from quarter pole to finish line or other portions of the track so photographed, may be reviewed in such manner as to impart a picture approximating to the observer a third-dimensional view.

These objectives and advantages of the novel method of this invention will be more readily understood from the following description thereof taken in connection with the appended drawings, in which:

Figure 1 is a diagrammatic view of a race track showing the respective positions of the two cameras utilized and the control connections therefor;

Figure 2 is a diagrammatic view of two motion picture projectors synchronously projecting a side and front view of the race at any given moment upon a movie screen.

It is to be understood that although these diagrammatic views relate particularly to application of the invention to the homestretch straightaway, from about the quarter pole to the finish line, this is for illustrative purposes only, as the

invention, utilizing similar camera control, is equally applicable and operative with respect to any other portions of the track.

Referring more particularly to the drawings, it will be seen that a race track 1 of usual oval configuration, having a finish line as indicated, distance divider poles as also indicated and entering chutes at opposite ends thereof, is subject to the view of two cameras 2 and 4. It has been found that the camera designated 2 is most ideally located at a relatively high position, here being placed at one end of the grandstand, a short distance towards the quarter pole (meaning a distance of a quarter of a mile from the finish line). Actually, the preferred position of this camera is near the one-eighth pole (meaning a distance of $\frac{1}{8}$ of a mile from the finish line). This is most favorable for the panning of this camera from quarter pole to finish line. The second camera 4 is positioned at a similarly sufficiently high elevation to obtain a clear view of the track and at the opposite end thereof where it takes a picture centered down the straightaway toward the quarter pole.

Both of these cameras are provided with synchronous motors 6 and 8. It has been found that a 16 mm. camera equipped with a 110 volt, 60 cycle synchronous motor is desirable as the type of equipment to be used with the method comprising this invention. For driving these two cameras, a common electric source is utilized as indicated in Figure 1. This source is comprised of two main lines L1 and L2, both of which lead to the respective motors 6 and 8. Both of these motors are in parallel circuit with each other, thereby assuring simultaneous control of the same. All precautions must be taken to assure that the current delivered to each of these cameras is of full voltage and of exact cycle in order that synchronism of the two cameras is mechanically accomplished without failure. Any type of synchronous motor is suitable, however, the purpose and operation of such devices being well known in the art.

In the positions of the two cameras, it will be noted that camera 2, having a view of at least the arc A, Figure 1, by such view obtains a clear picture of the track commencing at the quarter pole. This camera is adapted to pan or follow the subjects until it reaches the position identified by the arc B which intersects, or may, if desirable, go slightly past, the finish line. In contrast to the motion imparted to camera 2 by the operator as the race is panned from the quarter pole to the finish line, camera 4 is preferably maintained in relatively fixed position as indicated, having a view approximating the size of the arc indicated at C. Thus, camera 4 obtains a full view of the straightaway from the quarter pole to a position well past the finish line; in other words, a front view of the on-coming horses or contestants from the quarter pole to the finish line.

At a point indicated at dotted line D-D, camera 2 is exactly at right angles to the track and would obtain a true broadside or side view of the race. I have found it preferable to locate camera 2 at the position indicated, or spaced a short distance towards the quarter pole from the finish line, there being a sufficient transverse view from either side of point D-D to the finish line to obtain the desired purposes of the invention. It is known that a great many fouls originate between the quarter pole or a

slight distance past the quarter pole and the finish line, and that at the finish line, behavior of the contestants is critical. Therefore, camera 2, located in this position, obtains a maximum coverage of that area.

The operators of these cameras are professional cameramen having the ability to keep the race in constant focus in the designated area from the quarter pole to the finish line, and similarly, if required, on other portions of the track. One of these operators, preferably the operator of camera 4, is in complete control of both cameras, insofar as actuation of timing of the cameras be concerned. Thus, as soon as this operator views the race as it progresses towards and past the quarter pole, he places both cameras in operation. This control of both cameras is obtained by this operator by means of a switch 10, herein diagrammatically illustrated, which is so placed as to be within easy reach of the operator of camera 4. Switch 10 breaks the parallel circuit to both cameras and, when closed, both cameras are simultaneously actuated in parallel circuit 25 for the film recording of the race.

A few moments prior to the actual running of the race, each man loads his camera with film and places a "sync" mark, or a mark enabling synchronization of the film, on that portion or frame of the film which lies behind the lens. This sync mark may be made by means of an ordinary lead pencil or in any other suitable manner which will readily indicate the frame at which the initial picture of the film is taken. As the horses reach a predetermined point nearing the top of the stretch containing the finish line, the man in the controlling position of camera 4 turns both cameras on simultaneously by means of the aforementioned electrical switch. It is thus obvious that both cameras commence operation at a predetermined and marked frame. At that time, both operators commence to aim and pan their respective cameras until the horses have crossed the finish line at which time the operator of camera 4 throws the switch off. A convenient warning signal, such as a buzzer system or telephone, may be flashed to operator of camera 2 by operator of camera 4 just prior to the latter's placing the two cameras in operation.

After the pictures have been taken in the manner described, the film is transported to the processing laboratory, located in the paddock. The film is then processed as rapidly as possible in order that the pictures may be used to aid the stewards and judges in making a decision in case of a subsequent inquiry, objection or close question. It has been found that these films may be processed in approximately five and one-half minutes from the time the pictures enter the machine, and, accordingly, within this short time, the results of the photography are available to the interested officials.

The two films are then placed in two projectors 12 and 15 for viewing upon the usual type of screen 22. Both pictures are projected on the screen adjacent each other and close together. The films are set in the projectors with each of the sync marks respectively placed as the first frame to show up in each projector. In other words, the sync marked frames are placed behind the respective projector lenses. In this manner, the films are coordinated at the beginning of projection thereof. The two films are kept in 70 synchronism throughout the showing thereof by

driving the two projectors 12 and 15 by a common drive shaft 17. It is apparent that this type of synchronism is entirely mechanical and assures against failure of synchronization so far as projection of the film be concerned. Thus, with the projectors in operation, the resultant images on the screen are a side view of the race from quarter pole to finish line on one side of the screen, and a head-on view of the race from quarter pole to finish line on the other side of the screen.

With respect to synchronization during taking of the pictures, it has been found that the two cameras 2 and 4 will not differ in total pictures exposed by more than three frames. The average length of film used in each camera is approximately seventeen feet. There being forty pictures per foot of 16 mm. film, this would mean that each camera photographs six-hundred-eighty individual pictures. Cameras of the type preferred in the practice of this invention operate at twenty-four frames per second which means that each picture is taken at one-fiftieth part of a second. Inasmuch as horse racing, in general, is timed at one-fifth of a second, this type of motion picture coverage will assure adequate precision with regard to the time element.

It will be seen by the practice of the foregoing method that whereas previously purely visual observations of the race were officially from the stewards' stand, or from the viewpoint of the patrol judges in their towers, it was possible for inaccuracies to result and injustice to be done in certain instances. By the practice of the instant invention, mechanical recordation of the races is assured during whatever section or sections of the races are to be examined. Thus in the event of the stewards', or judges', decision being questioned, recourse may be had to the viewing of the precisely synchronized film of the race which will accurately and explicitly enable the officials to arrive at a correct decision, and avoid an incorrect decision. The advantage of this invention is that either layman or expert is given an actual view of the race as if seen by two individuals. This invention actually enables one person to view these two scenes on a screen at one time. In effect, what is being shown on that screen is a third dimensional view providing for a method of recording a race in such manner that it is practically impossible to overlook a foul, or to arrive at other than an accurate decision as to the proper winner. The synchronous camera technique as exhibited by my invention is unique over previous systems of judging or filming races, and has been found most effective in settling disputes as to a time lapse, or a distance lapse. This technique enables race officials to refer to the motion picture films without any fear of a difference of any time between shots, enabling the officials in the confines of a private projection room to see a rerun of the race as it actually happened. The result is to afford the officials a two-way view both clear and sufficient, to become evidence on which to base their judgments.

As many variations are possible within the scope of this invention, notably its application to various portions of the track, I do not intend the same to be limited in any manner except as defined by the appended claims.

What I claim is:

1. The method of recording and reproducing a racing event about a track comprising the use of

separate motion picture cameras mounted on stationary bases, said cameras being spaced from each other approximately one quarter of a mile, each of said cameras being focused toward an identical section of track but from a different angle, exactly synchronizing said cameras by placing a synchronous marking on the first frame of the respective films to be used in each camera, placing the frames having the respective markings before the lens of each camera used, simultaneously actuating both cameras through a common control, said cameras being in parallel circuit, taking a first motion picture from a point enabling viewing the finish line to quarter pole section of the track from above and the side thereof, taking a second motion picture of the same event at the same time so that the film in both cameras is simultaneously exposed, said second motion picture being taken at the end of said track opposite said quarter pole for an end view of the event down the straightaway, simultaneously stopping both cameras through a common control, said cameras being positioned so as to take pictures on lines of sight approximately right angularly to each other, and simultaneously projecting both motion pictures by placing the frames having said synchronism marking before the lens of each respective projector and simultaneously actuating the respective projectors.

2. The method of recording and reproducing a racing event about a track comprising the use of separate stationary motion picture cameras spacing said cameras from each other a distance of approximately one-half the length of said track, each of said cameras being focused at the same space of said track but at a different angle thereto, synchronizing said cameras by placing a synchronism marking on the first frame of the respective films to be used in each camera, placing the respective markings before the lens of each camera used, positioning said cameras so as to take pictures on lines of sight approximately right angularly to each other, simultaneously actuating said cameras through a common control in parallel circuit with said cameras, taking a first motion picture from a point enabling viewing of said track from the quarter pole to the finish line, simultaneously taking a second motion picture of the same event at the same time and so that the film in both cameras is simultaneously exposed, said second motion picture being taken of said track down the straightaway thereof, said cameras being synchronized exactly with each other, whereby said cameras take simultaneous pictures of an identical section of track but from a different vantage point with respect thereto, and projecting both motion pictures by initially placing the frames having said synchronism markings before the lens of each respective projector, simultaneously actuating the respective projectors, and synchronizing said projectors by driving the same through a common drive shaft.
